[57] ABSTRACT

A wire-like spring clip and clip installing tool for clamping a retaining stake to a key joint forming strip for concrete slabs. The clip has a back portion transversely disposed against the retaining stake, and two prong-like arm portions extending under the lower edge of the forming strip and projecting upwardly against the back of the forming strip. The prong-like arm portions are spring biased to direct a compressing force in cooperation with the straight back portion, thereby firmly clamping the retaining stake against the forming strip. The installing tool which operates as a lever to facilitate installation of the clip on the retaining stake and forming strip comprises a flat rigid shank with a notched end for temporarily holding the clip for installation.

RETENTION CLIP FOR CONCRETE SLAB KEY JOINT FORMING STRIPS

This application is a continuation of application Ser. No. 851,994, filed Aug. 21, 1969, and now abandoned.

BACKGROUND OF THE INVENTION

In the construction of poured concrete slabs, it has been found that divider strips should be placed at discrete intervals to permit expansion and contraction of the hardened slabs with changes of temperature. To prevent vertical displacement of the slabs with respect to each other, the divider strip is fashioned into a key joint forming strip to provide for interlocking of adjacent slabs. For purposes of this disclosure the forming strip may be as described in U.S. Pat. No. 3,288,042 entitled "CONCRETE SLAB KEY JOINT FORMING STRIP."

The divider strip of the aforementioned patent is adapted to be suspended on suitable placed vertical retaining stakes driven into the ground to a predetermined level. The top of the stakes fit into a channel-shaped recess or socket formed by a folded upper edge of the forming strip. The retaining stakes may be secured at the top by crimping an edge or lip of the forming strip into an adjacent aperture in the top of the stakes. However, when secured solely at the top of the stakes, the forming strip has a tendency to swing or lift when concrete is poured against the strip.

SUMMARY OF THE INVENTION

The present invention comprises a wire-like spring clip which clamps the thin, flat, lower edge of the forming strip to the retaining stake, thus firmly securing the stake to the forming strip at two separate locations. The clip thereby prevents any dislocation of the forming strip during pouring of the concrete.

To facilitate installation of the clips, an installing tool has been devised. The installing tool preferably comprises a flat metal shank with two corner notches which hold the clip at the end of the tool. Utilizing the leverage of the tool, the clip may be snapped onto the stake and forming strip.

BRIEF DESCRIPTION OF THE DRAWING

FIG. 1 is a side elevational view of the spring clip clamping a retaining stake to a section of a forming strip in a section of concrete.

FIG. 2 is a perspective view of the spring clip.

FIG. 3 is a perspective view of the spring clip, retaining stake and forming strip.

FIG. 4 is an enlarged sectional view taken on the lines 4-4 of FIG. 3.

FIG. 5 is an enlarged sectional view taken on the lines 5-5 of FIG. 3.

FIG. 6 is a perspective view of the clip and installing tool.

FIG. 7 is an enlarged, partial plan view of the clip and installing tool.

PREFERRED EMBODIMENT

Referring to FIG. 1, the spring is designated 10 and is illustrated clamping a retaining stake 12 to a forming strip 14. The retaining stake 12 is embedded in a prepared subgrade 16 and supports the forming strip 14 prior to pouring concrete. For added strength to the concrete, reinforcing rods, exemplar 18, may be inserted through holes (exemplar designated by numeral

19 in FIG. 2) in the forming strip 14, joining separate portions of a concrete slab 20. Concrete may be poured on either side of the forming strip 14 without causing the strip to swing or float upward which, without the clip, might otherwise result during pouring.

Turning to FIG. 2, the particular structural formation of the clip 10 can be observed. The wire-like clip is comprised of a substantially straight back portion 10a and two prong-like arm portions 10b which extend 10 downwardly from the back portion 10a, loop and project upwardly in a parallel manner. The ends of the prong-like arm portions 10b, designated 10c, are bent slightly away from the back portion 10a to enable the clip to be installed without snagging on the forming strip 14.

In FIG. 3, the spring clip 10 is illustrated in its clamping position holding the retaining stake 12 firmly against the thin, flat, lower edge 22 of the forming strip 14. The upper edge 24 of the forming strip 14 is folded over and formed into a substantially inverted Y-shaped section defining a channel-shaped recess 26 into which the top of the stake 12 is inserted. The stake 12 is provided with a semicircular aperture 28 into which the lip 30 on the upper edge of the forming strip may be crimped as illustrated in FIG. 3. In this manner the stake 12 is held firmly against the forming strip at two separate locations and will not become dislocated during concrete pouring.

FIGS. 4 and 5 disclose enlarged views of the spring clip 10 clamping the retaining stake 12 to the forming strip 14. FIG. 4 discloses with greater clarity the parallel looping of the two prong-like arm portions under the lower edge 22 of the forming strip to clamp against the back 14a of the strip. In FIG. 5, it will be observed that the outward bend at each of the ends 10c of the spring clip creates a condition in which there results a single point of contact for each prong-like arm portion against the back 14a of the forming strip. The two contact points of the prong and the contact point of the straight back portion 10a transversely disposed against the retaining stake define a plane perpendicular to the stake for an effective opposed clamping action.

FIGS. 6 and 7 illustrate the clip and an installing tool 32 which has been devised to facilitate installation of the clip on the stake and strip.

The installing tool 32 comprises a flat rigid shank with a contoured end 34 which matches any curvature of the stake 12. (Here the stake curvature can be seen in FIG. 4.) At the corners of the curved end 34 are two pommel-like protuberances 36 which cooperate with two notches 38 to form a seat for the clip. The clip is slipped into the notches in a yoke-like manner around the end 34 of the tool with the ends 10c of the two prong-like arm portions 10b of the clip pointing upwardly as shown in FIG. 6. With the clip so positioned, it is installed by first placing the curved end 34 of the installing tool 32 perpendicularly against the curved stake 12 below the lower edge 22 of the forming strip 14 and then sliding the end of the tool up the stake. The clip is thus forced to snap over the lower edge 22 of the forming strip 14 and into place. The tool is then twisted slightly to disengage the tool from the clip.

As can be seen in FIG. 6, opposite the curved end, the tool is fabricated with a broad notched end 40 having an extension 42 at each corner of the tool. The notched end 40 provides a convenient tool for straightening any clip which may have become slightly disori-

ented when disengaging the tool from the clip. The notched end 40 is simply placed against the stake with the two extensions straddling the stake's edge. An upward movement against the clip will adjust the clip to a proper seating.

The notched end 40 may also be used to disengage the clip from the stake and strip if desired. For this operation the notched end 40 is placed against the stake just above the clip at an acute angle from the top of the stake. By pushing the end downward the clip 10 will be disengaged from the forming strip 14 and retaining stake 12.

While the clip has been illustrated and described for use with a stake having an aperture into which the strip may be crimped for retention purposes, it should be understood that the clip is not limited to such use. Under most circumstances it will be found that the clip retains the stake against the strip with sufficient force that the crimping action is not necessary.

I claim:

1. In the combination comprising:

- a. a concrete key joint forming strip of the type having suspension means on the upper portion and a free lower edge; and,
  - b. a generally vertically disposed stake having the upper end thereof received within the inverted channel-shaped upper portion of the strip to effect support of the strip in a condition wherein the lower edge of the strip rests against the stake;
- the improvement comprising a spring clip for clamping the lower edge of the strip to the stake, said clip having a back portion which transversely disposes against the stake for contact therewith, and two pronglike arm por-

tions which extend downwardly from the back portion and around the edges of the stake, loop under the lower edge of the forming strip, and extend upwardly into engagement with the forming strip, said arm portions being bent to form sections which extend into spring biased clamping engagement with the strip, said sections and said back portion clamping the stake and forming strip therebetween.

2. In the combination comprising:

- a. a concrete key joint forming strip of the type having an inverted channel-shaped upper portion and a free lower edge; and,
  - b. a generally vertically disposed stake having the upper end thereof received within the inverted channel-shaped upper portion of the strip to effect support of the strip in a condition wherein the lower edge of the strip rests against the stake;
- the improvement comprising a spring clip for clamping the lower edge of the strip to the stake, said clip having
- 20 a back portion which transversely disposes against the stake in point contact therewith, and two pronglike arm portions which extend downwardly from the back portion and around the edges of the stake, loop under the lower edge of the forming strip, and extend upwardly into engagement with the forming strip; said arm portions being spring biased to force the forming strip against the stake and having ends which are bent away from the lower edge of the forming strip such that the upward extension of each arm portion has point contact against the forming strip, said points of contact of the arm portions and the back portion defining a plane extending transversely to the stake.

UNITED STATES PATENT OFFICE
CERTIFICATE OF CORRECTION

Patent No. 3,736,013 Dated May 29, 1973

Inventor(s) Phillip S. Hunter

It is certified that error appears in the above-identified patent and that said Letters Patent are hereby corrected as shown below:

Column 3, line 23, after "portion" insert -- for receiving the upper end of a stake --.

Column 3, lines 26 and 27, delete "inverted channel-shaped" and substitute therefor -- suspension means on the --.

Column 4, line 11, delete "an inverted channel-shaped" and substitute therefor -- suspension means on the --.

Column 4, line 11, after "portion" insert -- for receiving the upper end of a stake --.

Column 4, lines 14 and 15, delete "inverted channel-shaped" and substitute therefor -- suspension means on the --.
